Application August 24, 1933, Serial No. 686,585

21 Claims. (Cl. 101—252)

This invention relates to printing presses.

In offset printing, an inked impression is made on a rubber-covered or composition roller and then transferred to the paper. As the offset roller 5 moves across the type, it receives an impression which is the reverse of the type. When this impression is transferred to the paper it is again reversed, so that the impression on the paper reads in the same direction as the type. Offset printing presses therefore require special forward reading type and can not be used with standard type.

Offset printing can be done from standard type if double offset rollers are employed to effect three reversals of the impression in transferring it from 15 the type to the paper, thus producing a final forward reading impression on the paper from standard reverse type.

It is an object of this invention to provide an improved double offset printing press having novel 20 features and combinations of elements which simplify the mechanism of the press and make it economical to manufacture and convenient and advantageous in use.

Another object of the invention is to provide a 25 printing press which prints on the top sheet of a stack of paper and has means for removing the top sheet from the stack after each printing operation, and mechanism for raising the stack, as each top sheet is removed, to maintain the top 30 of the stack at a substantially constant level. The invention thus eliminates the conventional platen and paper-feeding mechanism.

Another object of the invention is to provide a 35 press having double offset printing means for printing on the top sheet of a stack.

Other objects, features and advantages of the invention will appear or be pointed out as the specification proceeds.

In the accompanying drawings, forming part 40 hereof:

Fig. 1 is a side elevation of a printing press made in accordance with the invention;

Fig. 2 is a top plan view of the printing press shown in Fig. 1;

Fig. 3 is an end elevation looking to the left in Fig. 1;

Fig. 4 is an enlarged fragmentary diagrammatic detail view of parts of the operating mechanism;

Fig. 5 is an enlarged fragmentary detail view 50 of the mechanism for operating the paper-holding and sheet-removing means; and

Fig. 6 is a sectional view on the line 6—6 of Fig. 5, and also shows the side frame and a part of the offset rollers with their operating mecha- 55 nism.

Each side of the printing press frame includes a base 11, a side frame 13, a pillar 15 extending from the base to an overhanging end of the side frame, a column 17, and a beam 19 supported by the pillar and column. Both sides of the frame 5 are connected by cross members 21, 22 (Fig. 3) to form a rigid structure. Certain other parts of the press which will be described connect with both sides of the frame and add to the rigidity of the structure.

The type is held in a chase 23 carried by a chase bed 25 (Fig. 2), which is connected to the side frames 13. Plates or other type substitutes can be used. An ink plate 27 is rotatably supported by the cross member 22.

Referring to Fig. 1, a carriage 29 is hung from the side frame 13 by carriage suspension links 30, which are pivotally connected to the side frame and carriage. A truck 32 slides on track 34 formed on the carriage 29. Rollers 35 and 36 are carried by the truck. Gears 37 and 38 are fixed to the rollers 35 and 36, respectively, and these gears mesh with one another so that neither of the rollers can turn without turning the other. The gear 37 meshes with a rack 40, which is fastened to the carriage 29.

The truck 32 is reciprocated on the carriage 29 by a connecting rod 42, which is pivotally connected at one end to the truck and at its other end to a crank 44. The crank is secured to a main shaft 45, and this main shaft is rotated by power mechanism, such as an electric motor.

The carriage 29 is moved laterally by a link 46 in timed relation to the reciprocating movement of the truck 32. Since the carriage is suspended from links 30, the lateral movement causes the carriage to raise and lower. The link 46 is cam operated by mechanism which will be explained in the description of Fig. 4.

The carriage suspension links 30, the gears 37 and 38, rack 40, connecting rod 42, crank 44 and link 46, shown in Fig. 1, are for one side of the printing press. Similar mechanism is located on the other side of the press to avoid twisting strains on the parts when the printing press is 45 in operation.

The roller 35 contacts with the type in the chase 23, and contacts with the lower roller 36 so that an impression which the roller 35 receives from the type is transferred to the lower 50 roller 36. Inking rolls 48 are supported by arms 49 of the truck 32 and move successively across the ink plate 27 and the type during each stroke of the truck.

A stack of paper 52 rests on a bed 54. The 55

bed slides vertically on the columns 17 and pillars 15. Paper-guides 56, 57 and 58 hold the stack of paper centered on the bed 54. The positions of these guides can be changed to accommodate 5 paper stacks having different size sheets. The paper-guides 57 are supported by a shaft 60, and have handles 62 which are operated to clamp the paper-guides against sliding on the shaft. When these handles are turned to unclamp the paper-guides from the shaft 60, the paper-guides are free to slide into any position on the shafts.

There are similar shafts 60 on the other side of the stack, as shown in Fig. 2. These shafts 60 are supported in movable blocks. Fig. 2 shows 15 blocks 64 at one end of the shafts 60. Similar blocks are located at the other ends of these shafts 60. The blocks 64 slide on a transverse beam 66, which connects with both sides of the frame. Each of the blocks 64 can be clamped 20 in any set position on the beam 66 by turning a clamping handle 68. The paper-guides 56 and 58 are similarly movable to accommodate paper stacks of different sizes. Since all of the paper-guides can be shifted, the stack of paper can be 25 moved on the bed if it is desirable to change the position of the impression on the paper.

Referring again to Fig. 1, the roller 36 contacts with the top sheet of the paper stack at each stroke of the truck 32. The impression which the 30 roller 35 takes from the type is transferred to the roller 36, and from this roller to the top sheet of the paper stack. The machine uses standard type which makes a forward impression on the roller 35. The impression is reversed when transferred to the roller 36, and reversed again in its transfer to the paper so that it again reads forward.

The top sheet of the stack is removed after 40 each stroke of the press by suction cups 12 operated by mechanism which will be described. The paper bed 54 is raised by chains 75 passing over 45 sprockets 76. These sprockets are operated to move the chains and raise the bed 54 a distance equal to the thickness of a sheet of paper for each stroke of the press. This paper-lift mechanism can be adjusted for sheets of different thickness, and will be explained in detail in the description of Fig. 4.

Fingers 80 (Fig. 2) hold the top sheet of the 50 stack to prevent movement while the impression is being made. The fingers 80 are operated by a shaft 82 which is supported by bearings in the paper-guides 56. The shaft 82 is rocked in timed relation to the reciprocating movement of the 55 truck 32 by a flexible shaft 84 which receives power from a link mechanism which will be explained in the description of Fig. 5.

The ink plate has a ratchet 88 (Fig. 1) which is rotated by a pawl 89 pivotally connected to a 60 crank arm 90 secured to a shaft 91. The shaft 91 is rocked by a crank 93, which is secured at one end to the shaft and at its other end to a connecting rod 95 operated by one of the links 30.

Fig. 4 shows the mechanism for moving the 65 carriage 29 laterally and for lifting the paper bed upward to raise the stack as the top sheets are removed during the operation of the press.

The link 46 is pivotally connected at one end to the carriage 29 and at its other end to a supporting link 100 which oscillates about a pin 102 extending from the side frame of the machine. The link 46 has a cam follower 103 operating in a groove 104 of a cam 106 secured to the main shaft 45. As the main shaft 45 rotates, the cam 75 groove 104 causes the carriage 29 to move later-

ally, and since the carriage is suspended on links 30 (Fig. 1), the lateral movement causes the carriage to raise and lower. The truck 32 makes one complete stroke for each revolution of the main shaft 45, and the cam groove 104 is shaped to cause the carriage to be raised so that the roller 34 contacts with the type when the truck 32 moves in one direction, and to cause the carriage to be lowered so that the roller 36 contacts with the top sheet of the paper stack when the truck 32 moves in the other direction.

Referring again to Fig. 4, the cam groove 104 also operates the mechanism for raising the bed 54 and stack of paper. The chains 75 pass over sprockets 76 on a shaft 110. The shaft and sprockets are turned by a worm wheel 112, which is secured to the shaft and driven by a worm gear 114.

The worm gear 114 is driven from a ratchet wheel 115 through bevel gears 116 and a shaft 118. The ratchet wheel 115 turns on a shaft 120 supported by the side frame of the press. A pawl 122 operates the ratchet and another pawl 124 holds the ratchet against reverse rotation. The pawls 122 and 124 are both moved into non-operative position when the bed 54 is to be lowered for a new stack of paper.

The pawl 122 is supported by a link 128 which oscillates on the shaft 120. The pawl is operated by a link 130, which is pivotally connected to a clamp 132. This clamp fits a curved arm of a lever 134 and can be held in any desired position on the lever by a clamping screw 136. A stud 138 extending from the side frame of the 30 35 40 45 50 55 60 65 70 75 80 85 90 95 100 105 110 115 120 125 130 135 138 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

Moving the clamp 132 closer to the stud 138 reduces the stroke of the link 130 and causes the pawl 122 to move the ratchet 115 through a smaller angle for each revolution of the main shaft 45 and cam 106. The mechanism is thus set to regulate the amount of rise of the paper bed for each printing operation of the press. When the sheets of paper are thin, a very gradual rise of the paper bed maintains the top of the stack at a substantially constant level, but with thicker sheets of paper the height of the stack is reduced more by the removal of a top sheet, and it is therefore necessary to raise the paper bed faster.

Fig. 5 shows the mechanism for oscillating the flexible shaft 84 and for removing the top sheet from the stack after each printing operation. An eccentric 150 on the main shaft 45 has a groove 152. A cam follower 154 on one end of a bell crank 156 fits the groove 152 and causes the bell crank to rock about a stud 158 as the eccentric rotates. The stud 158 is supported by the side frame of the press.

The other end of the bell crank 156 has a pivotal connection 160 to the upper link of a toggle 162. The lower link of the toggle oscillates on a stud 164 projecting from the side frame of the press. A slotted link 166 is pivotally connected at one end to the joint of the toggle, and at the other end to a crank arm 168, which is fastened to a shaft 170. This shaft 170 extends through the side frame, which serves as a bearing for the shaft, and is connected to the flexible shaft 84. A gear sector 172 is rotatably supported on an axle 174. A stud 178 on the gear sector extends 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

A gear sector 172 is rotatably supported on an axle 174. into the slot in the link 166, so that vertical movement of the link 166 imparts rotary movement to the gear sector 172.

Referring back to Fig. 2, there are bars 182 on both sides of the press. These bars are spaced from the side frames 13 and each bar supports a block 184. Each of these blocks 184 is slideable along its bar 182, and is clamped against sliding by clamping means operated by a handle 186. A shaft 188 has its opposite ends journaled in the blocks 184. Yokes 190 are fastened to the shaft 188 and these yokes support arms 192, to which the suction cups 72 are connected. The blocks 184 are moved into different positions 15 along the bars 182 to cause the suction cups 72 to grip the edge of the paper regardless of its size.

One of the arms 192 and its suction cup 72 are shown in Fig. 5. A pinion 196 on the end of 20 the shaft 188 meshes with the gear sector 172 so that rotary movement of the gear sector causes a rotation of the shaft 188. The axle 174 of the gear sector is carried by the block 184.

The yokes 190 are of such length, and the 25 upper ends of the arms 192 are so shaped, that, as the shaft 188 rotates, the arms 192 are first raised vertically and then rotated up and out, carrying with them the top sheet of paper which is held by the suction cups 72. A suction hose 30 198 connects each suction cup 72 with an air valve (not shown) for shutting off the suction when the arms are at the top of the stroke, so that the paper is released. Such valves are well known in the art and can be operated by the 35 shaft 188.

The slot in the link 166 permits the block 184 to be moved along the bar 182 to position the arms 192 and suction cups 72 to grip the edges of different size sheets without affecting the operation of the gear sector 172 by the vertical movement of the slotted link 166.

The operation of the printing press is as follows:

The main shaft 45 is power-driven to rotate 45 the crank 44 and cam 106. The crank causes the truck 32 to move to and fro on the carriage 29. The groove in the cam 106 is shaped to move the carriage 29 toward the right in Fig. 1, so that it is raised by the links 30 during the time 50 that the truck 32 is moving in one direction, thus causing the roller 35 and the inking rolls 48 to roll across the face of the type.

The groove of the cam 106 moves the carriage 29 to the left into the lowered position shown 55 in Fig. 1, where it remains while the offset roller 36 rolls across the top sheet of the paper stack 52.

While the top sheet is being printed it is held 60 against movement by the fingers 80. After the sheet is printed, the fingers are moved away from the paper by the shaft 82, which is rotated by the flexible shaft 84. The flexible shaft is operated from the shaft 170, which is oscillated by the mechanism shown in Fig. 5.

After the fingers 80 release the paper, the top 65 sheet is gripped by the suction cups 72 and removed from the stack. The pawl and ratchet mechanism shown in Fig. 4 turns the sprockets 76 enough at each stroke of the press to raise the bed 54 and stack of paper by a distance substantially equal to the thickness of a sheet of paper, thus maintaining the top of the stack at a substantially constant level during the operation of the press.

The invention can be employed for printing 75 on boxes or other objects having a relatively plane

surface, by successively placing the boxes or objects on the bed 54 in place of the stack of paper. The impression is made on the top side of the box or object in the same way as the top sheet of the stack is printed. The feed mechanism for raising the bed further with each printing operation is not necessary when printing on boxes. 5

The preferred embodiment of the invention has been described, but changes and modifications 10 may be made, and various features of the invention may be used alone or in combination with other features, without departing from the invention as defined in the claims. 15

I claim:

1. An offset printing press including an impression receiving roller; means for holding a stack of paper; means for moving the roller into contact with the top sheet of the stack and across the sheet to print the impression on said sheet; and means for removing the top sheet from the stack after each printing operation. 20

2. An offset printing press including an impression receiving roller; a bed for supporting a stack of paper; means for moving the roller into contact with the top sheet of the stack and across the sheet to print the impression on said sheet; means for removing the top sheet from the stack after each printing operation; and 25 mechanism for raising the bed to maintain the top of the stack at a substantially constant level. 30

3. In a printing press, means for printing on the top sheet of a stack of paper; means for holding the sheet against movement during printing; and mechanism for releasing the holding 35 means and removing the top sheet from the stack after the top sheet is printed.

4. A printing press including a bed for supporting a stack of paper; guides supported independently of the bed and in position to extend 40 along the sides of the stack to prevent it from shifting laterally; means for changing the positions of the guides to accommodate stacks having larger sheets; apparatus for printing on the top sheet of the stack; and mechanism for removing each sheet from the stack after it is printed. 45

5. A printing press including a bed for supporting a stack of paper; guides extending along the sides of the stack to prevent it from shifting laterally; apparatus for printing on the top sheet of the stack; mechanism for removing each sheet from the stack after it is printed; mechanism for raising the bed as the top sheets of the stack are removed so that the top of the stack remains 55 at a substantially constant level; guide-supporting means which remain stationary during the raising of the bed whereby the guides remain in substantially fixed relation to the top of the stack; and means for changing the positions of the guides to accommodate stacks having larger sheets. 60

6. A printing press comprising a chase for holding type; a truck; two offset rollers carried by the truck; mechanism for moving the truck 65 to alternately roll one of the offset rollers across the type and the other offset roller across a sheet of paper, said rollers contacting with one another to transfer the impression from the type-contacting roller to the paper-contacting roller. 70

7. In a printing press of the offset type, a carriage; a truck movable on the carriage between the type and the paper to be printed; offset roller means carried by the truck and movable across the face of the paper; mechanism for raising 75

- and lowering the carriage to move the offset roller means alternately into contact with the type and paper; and mechanism for reciprocating the truck on the carriage in timed relation 5 to the operation of the mechanism for raising and lowering the carriage.
8. A printing press comprising a frame; a carriage; links pivotally connected to the carriage and frame to support the carriage from the 10 frame; mechanism for reciprocating the carriage to oscillate said links and cause the carriage to move toward and from the frame; a truck supported by the carriage; offset roller means carried by the truck; and mechanism for reciprocating the truck on the carriage in timed relation to the operation of the mechanism for raising and lowering the carriage.
9. In a printing press, a carriage; printing means on the carriage for printing on the top 20 sheet of a stack of paper; mechanism for raising the stack of paper; mechanism for causing the carriage to raise and lower; and a common operating cam for both of said mechanisms.
10. In a printing press of the offset type, a 25 frame; a carriage supported by the frame and movable with respect to said frame; tracks on the carriage; a truck supported by the tracks; means for holding type; other means for supporting the work to be printed; offset roller means 30 carried by the truck; and mechanism for moving the truck with respect to the carriage to move said offset roller means across the faces of the type and work.
11. In a printing press of the offset type, a 35 frame; a carriage supported by the frame and movable with respect to said frame; tracks on the carriage; offset roller means; inking rolls; a truck supported by the tracks and carrying said offset roller means and inking rolls; means 40 for holding type; other means for supporting the work to be printed; and mechanism for moving the truck to and fro along the tracks to move the inking rolls across the type and the offset roller means across the faces of the type and work.
12. In a printing press, an offset roller for receiving an impression from type; another offset roller for transferring the impression from the first offset roller to a sheet of paper; a common truck carrying both offset rollers and movable 50 vertically and horizontally a gear connected with each roller and meshing with the gear of the other roller to cause said rollers to turn together, and means for causing the rollers to turn during the movement of the truck.
13. In a printing press, a carriage; a truck supported by the carriage; mechanism for moving the truck to and fro on the carriage; an offset roller for receiving an impression from type; another offset roller for transferring the impression from the first offset roller to a sheet of paper; bearings on the truck for both of the offset 60 rollers; a gear connected with each roller and meshing with the gear of the other roller to prevent slippage between the contacting faces of said rollers; and a rack on the carriage in position to mesh with one of said gears for all positions of the truck as it moves to and fro on the carriage.
14. A printing press comprising a bed for supporting a stack of paper; means for printing on the top sheet of the stack; mechanism for removing the top sheet from the stack after each operation of the printing means; mechanism for raising the bed and stack as the top sheets of the 70 stack are removed so that the top of the stack 75
- remains at a substantially constant level; and means for changing the rate of operation of the stack-raising mechanism to correspond to sheets of different thickness.
15. A printing press comprising a bed for supporting a stack of paper; guides extending along the sides of the stack to prevent it from shifting laterally; chains supporting the bed; sprockets over which the chains pass; means for printing on the top sheet of the stack; mechanism for removing the top sheet from the stack after each operation of the printing means; and mechanism for rotating the sprockets to cause the bed to rise and maintain the top of the stack at a substantially constant level as sheets are removed 15 after each printing operation.
16. A printing press comprising a bed for supporting a stack of paper; means for printing on the top sheet of the stack; mechanism for removing the top sheet from the stack after each operation of the printing means; mechanism for raising the bed and stack as the top sheets of the stack are removed so that the top of the stack remains at a substantially constant level, said mechanism for raising the bed and stack including pawl and ratchet means, a cam-operated lever for moving the pawl, and means for changing the effective length of said lever to vary the rate at which the bed and stack are raised.
17. A double offset printing press comprising a 30 roller for receiving an impression from type, a transfer roller in contact with the first roller for transferring the impression from the first roller to the top sheet of a stack of paper, a bed for holding the stack of paper, means for removing the top sheet from the stack after each printing operation, and feed mechanism for bringing the rollers and the bed progressively closer to allow for the diminishing height of the stack of paper as the successively printed sheets are removed.
18. A printing press comprising means for printing on the top sheet of a stack of paper, a bed for supporting the stack of paper, means for removing each sheet from the stack after it is printed, mechanism for moving the bed to maintain the top of the stack at a substantially constant level as successively printed sheets are removed, and guides extending along the sides of the stack to prevent it from shifting laterally, said guides being separate from the bed and stationary during the movement of the bed and stack, and means for changing the positions of the guides to accommodate stacks having sheets of different size.
19. In a printing press, means for printing on a stack of paper, and mechanism for automatically removing the top sheet from the stack after each printing operation including means for gripping the sheet near its edge, control means which can be set to cause the gripping means to grip near the edge of sheets of various sizes, and driving mechanism constructed and arranged to operate the gripping means for all positions of said control means.
20. A printing press including means for printing on the top sheet of a stack of paper, a bed on which the stack rests, mechanism for raising the bed progressively with each printing operation, guides on all four sides of the stack of paper, stationary supporting means for the guides so that said guides do not rise with the stack and bed, said supporting means being located below the top of the stack when the top sheet of the stack is in position to receive an impression from the printing means, and means for changing the 65 70 75 80 85 90 95

positions of all of the guides so that the stack can be shifted with respect to the printing means to change the position of the impression on the paper.

5 21. A printing press comprising a bed on which the work rests with the surface to be printed in a substantially fixed plane, roller means which reciprocate transversely to the face of the work to

be printed and which are located at a substantial distance above the bed for taking an impression from type and transferring it to the top surface of the work, mechanism for moving said roller means across the type and thereafter moving said roller means into rolling contact with the top surface of the work to be printed. 5
